Primary Examiner — Nathan M Johnston(74) *Attorney, Agent, or Firm* — Daniel M. Cohn;
Howard M. Cohn(57) **CLAIM**

The ornamental design for a tool storage rack as shown and described.

DESCRIPTION

FIG. 1 is a perspective view of a tool storage rack showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof; and,

FIG. 9 is an enlarged view of portion of FIG. 1.

The broken lines depict portions of the tool storage rack are for the purpose of illustrating article and form no part of the claimed design. The dash-dot-dash broken lines encircling the enlarged views are for annotative purposes only and form no part of the claim design.

1 Claim, 9 Drawing Sheets(56)
